(57) **CLAIM**

The ornamental design for an accessory for pet harness, as shown and described.

DESCRIPTION

FIG. 1 is a front, right and top perspective view of an accessory for pet harness, showing my design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof; and,

FIG. 8 is a rear, left and top perspective view of the accessory for pet harness when in use.

The broken lines in FIGS. 1-7 depict portions of the accessory for pet harness that form no part of the claimed design, while the additional broken lines in FIG. 8 depict environmental subject matter, specifically a harness and leash, that form no part of the claimed design.

1 Claim, 8 Drawing Sheets
